UNITED STATES PATENT OFFICE.

FRANK A. NIEBERDING, OF CLEVELAND, OHIO, ASSIGNOR TO THE GUARDIAN GAS APPLIANCE COMPANY, OF CLEVELAND, OHIO, A CORPORATION OF OHIO.

DESIGN FOR HEATER.

Application filed September 24, 1923. Serial No. 7,296. Term of patent 7 years.

To all whom it may concern:

Be it known that I, FRANK A. NIEBERDING, a citizen of the United States, residing at Cleveland, in the county of Cuyahoga and State of Ohio, have invented a new, original, and ornamental Design for Heaters, of which the following is a specification, reference being had to the accompanying

drawing, forming part hereof, wherein the figure is an elevation of a heater exhibiting my new design.

I claim:—

The ornamental design for heater, as shown.

FRANK A. NIEBERDING.
